(57) **CLAIM**

I claim the ornamental design for a model vehicle roof skid, as shown and described.

DESCRIPTION

FIG. 1 is an upper, left, front perspective view of a first embodiment of a left model vehicle roof skid showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof; and,

FIG. 7 is a lower plan view of the model vehicle roof skid. The broken lines in the drawings illustrate portions of the model vehicle roof skid that form no part of the claimed design.

In the drawings, only the first embodiment of the model vehicle roof skid is shown. The second embodiment of the claimed design is a right model vehicle roof skid which is a mirror image of the left model vehicle roof skid disclosed in the first embodiment.
